UNITED STATES PATENT OFFICE.

OSMAN B. KEMPTON, OF LANDER, WYOMING.

GATE-HINGE.

1,072,957.

Specification of Letters Patent.

Patented Sept. 9, 1913.

Application filed June 28, 1912. Serial No. 706,527.

To all whom it may concern:

Be it known that I, OSMAN B. KEMPTON, a citizen of the United States, residing at Lander, in the county of Fremont and State of Wyoming, have invented new and useful Improvements in Gate-Hinges, of which the following is a specification.

This invention relates to an improved gate hinge which will operate to effect a tilt of the gate as the latter is opened.

A still further object of the invention is to provide a hinge for the gate which will be adjustable whereby the tilt of the gate can be determined at the will of the operator.

A still further object of the invention is to provide a gate in which the hinge thereof will be simple of construction, inexpensive to manufacture and convenient for attachment to any standard form of gate.

In the drawing forming a portion of this application, and in which like letters of reference indicate similar parts in the several views: Figure 1 is a horizontal sectional view of the hinge member which is secured to the hinge post; and Fig. 2 is a horizontal sectional view of the hinge element secured to the supporting post.

In order that one can regulate the tilt of the gate to suit any particular demand I provide a hinge such as the one shown in Fig. 1 which includes substantially identically formed portions 33 and 34 of the hinge element 35 upon the hinge post 36 of the gate. The portions 33 and 34 have rabbeted inner ends 36 which are slidable over each other and provided with elongated horizontal registering slots 37. The said intermediate rabbeted portions are mounted in a horizontal recess 38 in the hinge post of the gate and through the post and through the slots 37 is passed a bolt 38' whose clamping nuts may be adjusted to retain adjustments of the portions 33 and 34 as will be understood.

In the modification of the invention illustrated in Fig. 2 it will be seen that the hinge element 39 of the supporting post of the gate frame is substantially identical in construction with the element 35, being provided with relatively adjustable sections 40 and 41 and a bolt 42 for holding the sections in adjusted positions. Now it is evident from the construction last described that the hinge pintles 43 of the element 39 can be adjusted laterally with relation to the upper hinge pintle of the gate. In other words the lower pintles can be adjusted with relation to the upper hinge of the gate whereby any desired tilt of the gate can be obtained and in this manner the gate in operation will rise angularly sufficiently to cause its escape from large obstructions that may lie in its path.

I claim:—

1. In combination with a swinging gate of plates adjustable horizontally upon the hinge post of the gate, a supporting post having plates provided with pintles adjustable toward and away from each other and operatively associated with the plates of the hinge post of the gate so as to furnish a fulcrum for the latter, and means hingedly connecting the upper end of the hinge post of the gate with said supporting post.

2. A hinge member comprising relatively adjustable sections, hinge pintles carried by the sections, and means by which the sections may be secured in adjustable position and secured to a support.

In testimony whereof I affix my signature in presence of two witnesses.

OSMAN B. KEMPTON.
